CENTRIFUGAL CASTING MACHINE

George A. Rubisow, New York, N. Y.

Application April 21, 1947, Serial No. 742,880

5 Claims. (Cl. 22—65)

1

This invention is a continuation in part of the following applications for Letters Patent Ser. No. 547,307, filed on July 29, 1944, for Centrifugal Casting Machine and Devices Therefor; Ser. No. 535,475, filed on May 13, 1944, for Molds for Centrifugal Casting and Methods Therefor, and Ser. No. 539,517, filed on June 9, 1944, for Devices and Molds for Centrifugal Casting and/or Forging, which all three beforementioned applications have been abandoned.

This invention provides a method and means for centrifugal castings and comprises an independent rotating pouring gate, its combination with molds and with means to control the excess overflow of molten material, if any.

Like references are used throughout this description and drawings will be used to describe like subject matter.

Only one example of the machine is illustrated, but this invention is not limited thereto.

Fig. 1 is a side view, partly in cross-section with parts broken out of one embodiment of this invention, shown in simplified semi-schematical manner.

Fig. 2 is a plan view of Fig. 1.

Fig. 3 is a side view of Fig. 1 with some parts broken out.

Fig. 4 is an enlarged cross-sectional schematic view along axis Z—Z of Fig. 2 with parts broken out, of a gate mold interconnecting means, gate and mold.

Fig. 5 is a side view of a portion of Fig. 2.

Fig. 6 is a plan view of a portion of Fig. 2.

Fig. 7 is a schematical cross-sectional side view with parts broken out of another embodiment of gate mold interconnecting means.

Fig. 8 is a schematical plan view of Fig. 7.

Fig. 9 is a schematical plan view partly in cross section of another embodiment.

Fig. 10 is a simplified semi-schematical side view in cross section of another embodiment.

Fig. 11 is a plan view of Fig. 10 when top guard 61A is removed.

One aspect of this invention is shown in Figs. 1, 2 and 3, wherein the mold receiver 11, carrying a mold M is rotated around a vertical axis X—X, and wherein the molten material used for castings, and to be poured into this mold may be poured into it while the mold is in rotation, and wherein means are provided to evacuate any excess of the overpoured molten material, so that no excess material will remain either in the central pouring gate nor in the gates interconnecting it with the mold gate, and wherein such excess molten material will be evacuated

into the open or into a storage chamber provided therefor.

According to this invention a mold receiver 11, is mounted rigidly on a collar support 12, provided with a pulley 13 (or with a bevel gear and the like). Said mold receiver 11 is mounted rotatably through the intermediary of bearings 14, 14 and 15, on a non-rotatable shaft 10, mounted rigidly on a support 16, mounted on the ground 16A, preferably with the assistance of a reinforcement plate 17, or the like means.

Although the illustrated herein machine for centrifugal castings shows a non-rotatable shaft, on which is rotatably mounted a mold receiver, it is obvious that a rotating shaft which is rigid with a mold receiver 11, may be used, and in this latter case, bearing means should be provided in a bearing support, rigidly mounted in respect to the ground, in order to permit the rotation of the shaft together with the mold receiver.

When a non-rotatable shaft as shown in Figs. 1, 2 and 3 is used, then the mold receiver 11, is rotated itself by a belt, chain or gear drive or otherwise.

25 The mold receiver 11, is provided with one or more molds or is provided with mold casings in which molds are placed. The use of casings for molds is recommended, when molds are not strong enough.

30 In order to keep the mold in a tight position in the mold receiver, insertion members 18, or key members 18A and 18B, may be provided. The mold receiver has a gate casing support and guide member 27, which may be of any form, 35 for instance, have a circular or square form, or may consist only of few bars or guides, rigid with the mold receiver.

The rotating pouring gate RG, is mounted so that it can slide to-and-fro in respect to the axis 40 of rotation X—X, while being guided in guide means 29, provided on or in the member 27. The rotating gate RG may comprise a gate casing 22 in which a gate 21 is flaring downwardly from the gate entrance 19, towards the bottom part 45 40, where two exit orifices 20, 20 are provided. The rotating gate RG may take any predetermined position on the guide means 29, and may be (before and/or during the rotation of the machine) so maintained thereon by mechanical

50 means or by hydraulical or pneumatic means, such as for instance, by means of a piston 32, mounted in a cylinder 35, provided in a shaft 10, and controlled by means of a pump 37 (not shown), which pump is interconnected with the 55 cylinder through conduits 36. The top part of

the piston 32, may contact the bottom part of the gate casing of the rotating gate RG directly or through a collar 34, rigid with the bottom 30 of the gate casing, in which collar 34 is mounted a member 33 provided on the top of the piston 32.

The rotating gate RG is rotating together with the mold receiver 11, and forms one rigid body therewith after it is adjusted to any desired predetermined position, or even during its rotation. The rotating gate RG is so positioned, that its exit orifice 26, substantially registers the entrance of the main gate of the mold M, or molds M1, M2, etc. (not shown), if more molds are provided. In Figs. 1, 2 and 3, is shown a machine having two molds and having thus two exit orifices, provided in the rotating gate RG, and it is obvious that when three molds are used, three exit orifices should be provided in the rotating gate RG. The rotating gate RG may be made from one solid piece or may comprise a casing 22, in which a refractory 23 or other materials is provided.

A main entrance orifice 19 is provided on the top of the pouring gate RG, and at least one exit orifice 20 is provided on or near its bottom 40. The outer part of such exit orifice 20 is interconnected by a suitable exit channel 26 (which channel may be of any form or shape, flaring or tapering), with gate mold interconnecting means R4, interconnecting the rotating gate RG with the mold M through the channel 24. The bottom 40 of the rotating gate may be so shaped that the diameter D2 is smaller than D1, such an arrangement will force molten material to the orifices 20, 20 and thus no material could remain in the rotating gate after the casting is performed. It is not recommended that D2 is equal to D1, and D1 should be at least slightly, even very slightly greater than D2. The rotating gate RG may be provided on its sides with one or more collars 25 which may slide to-and-fro along the guides 29. The guides 29 may have flanges 38 provided on the edges of a cut out 39, for a better control of the movements of the rotating gate RG therein.

The exit orifice 20 of the rotating gate RG may contact directly the mold M so that the exit orifice 20 and the entrance gate G of the mold will form one continued channel, this is not shown, being self evident.

The exit orifice 20 may also according to this invention contact the mold gate G through a gate mold interconnecting means such as R1, R2, R3, as shown in Figs. 1, 2 and 3, and in other figures. This means R1 may be made of any suitable solid, including metal, metal alloys, whenever it may be used; or from refractories including such as asbestos, rockwool, powdered mica, etc., or any combination of them, according to requirement. The gate mold interconnecting means may according to this invention, be provided with a channel 41-42-43 Figs. 4 and 5. When using a tapering channel, the flow of the molten material therein, will be under compression, due to the diminishing of its cross-section. In Figs. 4 and 5 is shown such a tapering channel 24 wherein the entrance diameter 41 is larger than the exit diameter 42.

According to this invention, a special overflow exit passage 53 as shown in Figs. 4 and 5, is provided in such a manner that it discharges into a channel 24 or 41-42-43. This overflow exit passage 53 may have also a form as shown by 53 in Figs. 6, 7 and 8, and it may discharge into the

channel 24. This channel 24 and the overflow exit passage 53 are so designed that when an overflow of molten material, poured into rotating gate RG, will by chance occur, i. e. there will be present an excess of molten material which the mold could not hold, then this excess will be evacuated through this overflow exit passage 53 to the outside of the mold, and no molten material will remain in the rotating pouring gate. This is an extremely important feature of this invention for the centrifugal casting industry, and it will permit the use of machines having a rotating pouring gate independent of the mold. In such machines no molten material will remain after the pouring will be stopped and this notwithstanding the fact that the molten material was introduced into the molds through the rotating pouring gate, while both the rotating pouring gate and molds were rotated, and this notwithstanding the fact, that any overflow of the mold which may have happened, will not encumber the rotating pouring gate with excess of the molten material caused by overflowing, and this due to the overflow exit passage 53 through which any such excess-overflow of the molten material will be evacuated.

It is obvious that when the rotating gate RG Figs. 4 and 6, is rotated in the direction of the arrow A, the molten material, when leaving the orifice 26 of the rotating gate RG, will try to take a tangential direction. Should therefore an overflow occur, i. e. the gate G in the mold M, Figs. 4 and 6, will be filled with the molten material until the level 47, and the molten material will rise still higher, then the molten material having no further place and room to go in the mold M or in the gate G, will obligatorily be forced to escape through the passage 53. According to this invention, it is advisable to provide the overflow exit 53 in the same direction as the direction of rotation, and this speaking in terms of vector, i. e., a tangent taken at the point where the overflow exit passage 53 is passing in regard to the rotation around axis X-X. As shown in Figs. 2, 4, 6 and 8, the overflow exit passage 53 is provided substantially in the plane of rotation, i. e., in the plane perpendicular to the axis X-X of rotation, and at the same time, in the direction of rotation, i. e., in the direction of the vector-tangent.

It is advisable that the channels 41, 42, 43 and 24, are so designed that no molten material will enter into the overflow exit passage 53, unless an overflow occurs. Some of such particular embodiments, but not limiting this invention thereto, are shown herein, in Figs. 4 and 5, wherein the diameter of the channel 24, is slightly tapering from 41 to 42, and thereafter, the diameter is making a sudden enlargement to its original diameter 41, at which place of such enlargement, the overflow exit passage is taking its beginning. The latter diameter 41 may thereafter again increase in its cross-section from 41 to 43, or to the cross-section of the mold gate G. The wall 54 at the height of the overflow exit passage will receive a pressure of the molten material in the direction of the rotation, and at the same time there will be no pressure and no movement of the molten material in the passage 53 unless an overflow has occurred. The overflow exit passage 53 may be tapering or flaring according to results desired to be obtained. The flaring passage shown in Figs. 4, 5, 7 and 8, is advantageous. As it is shown, it starts with the relatively narrow cross-section 48 flaring to 49, and if provided about the middle of the body of the gate mold

interconnecting means R3 (Figs. 7 and 8). In Figs. 4, 5 and 6, the passage 53 is provided in that part of the means R1 and R2, which touch the mold M. When using means R3, it is necessary that the molten material substantially reaches the plane 46 in order that the evacuation of the excess overflow material is started through the passages 48 and 49.

The gate mold interconnecting means R1, R2, R3, may be used for single rotation of the mold as herein described, as well also for molds which are rotated simultaneously around two axes of rotation, in which latter event, it is not necessary that the gate mold interconnecting means do contact tightly the rotating pouring gate. Such arrangements for molds rotatable simultaneously about two axes of rotation (double rotation), could use the invention herein described without departing from the scope of this invention.

The overflow exit passage 53 may discharge itself by its outer end either into an open, as does passage 53B, Figs. 1, 2 and 3, in which case the molten material will flow out into the open, i. e. outside of the rotating machine, or the molten material could be discharged through a passage 53A (Figs. 1, 2 and 3) into a safety chamber CH, provided accordingly either in the mold itself (i. e. in that part of it which may be used for this purpose) or it may be evacuated outside of the mold into a safety chamber CH provided between the mold and the mold receiver 11.

The molten material flowing through the mold gate G is distributed through various distributing gates G1, etc., and will fill the mold cavities S, S, either from the back of it, in regard to the axis of rotation X—X, or otherwise. The backward feeding in respect to the direction of the centrifugal force in combination with a sudden flaring distributing gate system will diminish the "pouring shock" between the pouring in molten material and the mold.

The gate mold interconnecting means R1, R2, R3, may be prefabricated as standards for the respective rotating pouring gates, and their exit channels 26, and they may be provided with recesses and flanges of any type and form, so that they may be placed without error in the right position particularly in respect to the overflow exit passage 53.

This invention is not limited to the use of the gate mold interconnecting means made in a form of a separate unit, i. e. separate from mold such as units R1, R2, R3, and it is obvious that this invention also comprises gate mold interconnecting means, which are an integral part of the mold, i. e. are provided in the mold itself. The functioning of such latter means is exactly the same as if they have been a unit separate from the mold, such as R1, R2 or R3.

When the overflow occurs the molten material will either pass into the overflow chamber CH where signal means could be placed to detect the overflow, such signal means for instance, may be a window 62 Fig. 2, made in the wall of the chamber CH and in the wall of the mold casing or in the mold receiver 11, so that detection may be made by sight when glare of molten material will appear from the overflow. Detection could also be made by sound because the overflow makes a specific audible sound, generally easily detectible during the pouring of the mold during rotation. When the overflow is made into the open, through the overflow passage 53-53B, Fig. 3, then, the detection may be made by sound or by sight or by means of a photo-electric cell.

It is natural that a centrifugal casting machine is generally provided with a guard 61 preferably surrounding the machine either from all sides and/or from the top or at least, from the side or a part of a side where men are working. Such guards 61 may be provided in any suitable place around the machine and may have in a desirable place a peep window 62 for sight-detection or have a photo-electric cell 60 for the detection of sound and/or of glare of the overflow. The windows may be provided with shock and heat resistance glass, quartz or mica plates for safety purposes.

Still another aspect of this invention is shown schematically in Fig. 9, wherein the mold receiver 11 may be cylindrical or in any other form, and may have at least one mold casing 11A mounted therein in which the mold or molds are placed. The rotating pouring gate RG is shown immersing into the gate-mold-interconnecting means, which in this arrangement is not a separate insertion member but is a part of the mold M, Fig. 9, which part is thus substituting for the gate-mold-interconnecting means. When the pouring of the molten material, such as for instance, molten steel, molten metals, molten metal alloys, molten glass, molten plastics, etc., is started, it first enters into the orifice 19 and thereafter it is distributed through the exit channels 28 and 24 into the gate mold G. The pouring is continued until the mold is filled and until the level of the molten material in the gate G has reached the curved level formed for instance by the radius D3. As soon as the cavities and the gate mold are filled, the molten material reaches the level D33, and if thereafter, the pouring is still continued, by mistake or for other purposes, the excess material will be forcedly carried away through the safety channel 115 placed inside of the mold M or outside of it.

An exit hole 117 may be provided in the mold casing 11A as an outlet for the channel 115, thus the molten material may be discharged into the open or into a storage chamber CH, which may be provided for this purpose in the vicinity of the mold or be attached to the mold or be a part of the mold.

The channel 115 may be inclined at any suitable angle, may be directed in any suitable plane and in any suitable direction in regard to the radius D3. It is essential that the beginning part of the overflow exit channel or passage will be so designed that its entering orifice is placed between that part of the gate mold G, where the predetermined level D3 starts, and above this level in the direction towards the axis of rotation X—X.

The channel 119 is provided in the mold M in a similar way as the channel 115, except that, 60 a part of it passes through the bottom of the mold, and that it changes its direction from a direction in a substantially tangential plane to the radius, of rotation in the beginning of the passage, to a substantially radial direction, in its main or middle part, and that it discharges into the open so that the material flowing through it will discharge into the storage chamber or into the space provided in the mold receiver, or available outside of the mold for such a purpose. 121 65 is the exit part of the channel which leads to the storage chamber CH, substituted in Fig. 9, by the free space in the mold, mold receiver 11. This embodiment also enables to make a choice 70 of the radius D3 so that it will become a con-

trolling factor for permissible or desirable position of the level D33 for the gate G of a mold M.

When the storage chamber is provided inside of the mold receiver 11 such as chamber CH in Fig. 2, the peep window 62 for sight detection should be provided in the wall of the mold receiver and also in the wall of the chamber as it is shown. If the guard 61 is used, then another peep window 62 or a photo-electric cell 60, or both, may be provided in the guard as shown in Fig. 2, and thus the glare and/or the noise or sound from the overflowing molten material will be detected through the windows 62 and 62 of the casing or of the mold receiver, or they will be detected by the photo-electric cell 60 when the same is registering respectively the window 62.

When a double rotation is used as shown schematically in Figs. 10 and 11, where the mold M is rotated simultaneously around two axes of rotation, axis X—X and axis Y—Y, and when the molten material is passing from the crucible, first through the main pouring gate 19 and thereafter through the exit orifice 20 and thereafter through the channel 24 into the gates G3 and G4. From thereon it passes into the cavities S3, S4, etc. of the mold. When the molten material has reached the level D5, D4, then having no other place to go, the molten material will forcibly flow into the overflow exit passage 53A, and it will be discharged through this passage 53B (which passes through the mold casing) into the open. It is obvious that with this machine, where the mold is rotated simultaneously around two axes of rotation X—X and Y—Y, the material will flow through the exit end 53B of the overflow exit passage 53A, and will thereafter fly out into the open around the mold casing 11A. For this reason, a guard 61 and 61A, should be provided all around the machine so that the molten material emerging from the passage 53A through end 53B will be temporarily stored inside of such a guard 61 and 61A. A peep window 62 and/or a photo-electric cell 60 as shown in Figs. 10 and 11, may be used to detect by sight and/or by sound the overflow of the molten material. The guard in this embodiment is substituting for the storage chamber.

The double rotating machine shown in Figs. 19 and 11 comprises the following components as one of the possible embodiments. There is a non-rotating gear 125 in mesh with rotating gears 123, mounted rotatably on thrust and radial load bearings, coaxial with axis Y—Y and which bearings together with the rotating gears 123 are mounted around a support member through which the gate 24 is passing. The mold casing 11A may be attached either by means of bayonet locking arrangement to a mold holding disc 124, or by means of a screwing arrangement, as does disc 124A. The discs 124 and 124A are coaxial with axis Y—Y and are rigidly mounted on the gears 123.

When the rotating or driving shaft RS is rotated, the mold casings 11A with the mold M are automatically rotated simultaneously around two axes of rotation X—X and Y—Y. If it is desirous that the mold casing 11A should be heated prior to or during the rotation then this may be achieved electrically by means of a collar with circular contact guides 130—131, mounted on the discs 124A and interconnected by means of friction contacts such as pusher contacts 132—133, and through other wires to the wires 134—135 through which the electric current will

be transmitted through the rotating pouring gate to the rotating mold casing into the heating element 126 provided therein. These wires may go through a collar guide contact 134 and thereafter through another friction contact and finally to the outside through the guard 61 where a current could be supplied from any source and for any purpose, through the wires 134—135. A heat resistance casing 126 may be provided in the mold, and may be heated through the wires 137—138. If desired a high-frequency heating coil may be mounted in or around the casing 126.

Another embodiment is shown where the gate 127 is extending substantially up to the bottom of the mold casing 11A (on the right side of the drawings in Figs. 10 and 11), and this gate may be used in particular, for centrifugal separation of metal alloys or other molten materials or chemical fluids, which are composed of at least two different substances of a different specific weight mixed together but not combined chemically, the heavier substance will occupy the farthest away space from the axes "X—X and Y—Y." The light weight substance will try to come closer to these axes of rotation, in the direction of the resultant vectors of both centrifugal forces, in regard to X—X and Y—Y, for instance occupy the space between the levels 128 and 129. This arrangement therefore will permit two continuously pouring in of the molten or liquid material into the rotating container 11A, while the lighter substance composing this material will be continuously evacuated as soon as it reaches the level 129 through the overflow exit passage 53C, thus accomplishing a perfect and a quicker separation by double centrifugal force. If desired, the same principle of separation may be achieved in a single rotation arrangement, i. e. in the case of the above drawings of Fig. 10, the rotation will be made only around the axis X—X and not around Y—Y, or only around Y—Y but not around X—X, or other machines such as shown in other figures may be used.

The reading of the U. S. Patents 2,222,266; 2,208,230, and 2,325,019, is recommended, as they may be used in conjunction with this invention.

What I claim is:

1. A known centrifugal casting machine having at least one mold rotatable around at least one axis of rotation, but not more than two axes of rotation, at least the first of said axes being eccentric to said mold, and having a frame with a central pouring gate rotatable about said first axis of rotation, said gate being provided on its top with an entrance orifice for the pouring in of molten material, and provided on its bottom with a distributing channel to feed said molten material therethrough from said gate to said mold, a free empty space provided between said channel and said mold, said known machine in combination with: a substantially large safety overflow passage provided in said free empty space in the direction coinciding with the direction of rotation around said first axis of rotation, the entrance orifice of said passage being substantially large in cross section and adjacent to that part of said mold which is closest to said first axis of rotation, rigid means to maintain said passage in a rigid position in respect to said mold and said channel whereby when an excess of molten material is overflowing said mold, such excess is evacuated throughout said passage.
2. A known centrifugal casting machine having at least one mold rotatable around at least

one axis of rotation, but not more than two axes of rotation, at least the first of said axes being eccentric to said mold, and having a frame with a central pouring gate rotatable about said first axis of rotation, said gate being provided on its top with an entrance orifice for the pouring in of molten material, and provided on its bottom with a distributing channel to feed said molten material therethrough from said gate to said mold, a free empty space provided between said channel and said mold, said known machine in combination with: a substantially large safety overflow passage provided in said free empty space in the direction coinciding with the direction of rotation around said first axis of rotation, the entrance orifice of said passage being substantially large in cross section and adjacent to that part of said mold which is closest to said first axis of rotation, rigid means to maintain said passage in a rigid position in respect to said mold and said channel, said passage being in communication with a storage chamber provided therefor in said mold, whereby when an excess of molten material is overflowing said mold, such excess is evacuated throughout said passage into said storage chamber.

3. A known centrifugal casting machine having at least one mold rotatable around at least one axis of rotation, but not more than two axes of rotation, at least the first of said axes being eccentric to said mold, and having a frame with a central pouring gate rotatable about said first axis of rotation, said gate being provided on its top with an entrance orifice for the pouring in of molten material, and provided on its bottom with a distributing channel to feed said molten material therethrough from said gate to said mold, a free empty space provided between said channel and said mold, said known machine in combination with: a substantially large safety overflow passage provided in said free empty space in the direction coinciding with the direction of rotation around said first axis of rotation, the entrance orifice of said passage being substantially large in cross section and adjacent to that part of said mold which is closest to said first axis of rotation, rigid means to maintain said passage in a rigid position in respect to said mold and said channel, signal making means for detecting of the start of an overflow of molten material

- in said passage and for automatically signaling thereafter said detecting, whereby when an excess of molten material is overflowing said mold, such excess is evacuated throughout said passage and said signal making means automatically signal the start of said overflow.
4. A known centrifugal casting machine having at least one mold rotatable around at least one axis of rotation, but not more than two axes of rotation, at least the first of said axes being eccentric to said mold and having a frame with a central pouring gate rotatable about said first axis of rotation, said gate being provided on its top with an entrance orifice for the pouring in of molten material, and provided on its bottom with a distribution channel to feed said molten material therethrough from said gate to said mold, a free empty space provided between said channel and said mold, said known machine in combination with: a substantially large safety overflow passage provided in said free empty space in the direction coinciding with the direction of rotation around said first axis of rotation, the entrance orifice of said passage being substantially large in cross section and adjacent to that part of said mold which is closest to said first axis of rotation, rigid means to maintain said passage in a rigid position in respect to said mold and said channel, said means having a form of a flat insert interposed inbetween said channel and said mold, said passage being cut out in said insert whereby when an excess of molten material is overflowing said mold, such excess is evacuated throughout said passage.
5. A machine as set forth in claim 4 wherein said insert is made from asbestos.
